Primary Examiner—Susan J. Lucas**[57]****CLAIM**

The ornamental design for a magnetically mounted battery powered light, as shown and described.

DESCRIPTION

FIG. 1 is a perspective view of the magnetically mounted battery light;

FIG. 2 is a front elevational view of the light;

FIG. 3 is a right side elevational view of the light, the left side being a mirror image;

FIG. 4 is a top plan view of the light;

FIG. 5 is a rear elevational view of the light; and,

FIG. 6 is a bottom plan view of the light.
